(57) **CLAIM**

The ornamental design for a steering wheel, as shown and described.

DESCRIPTION

FIG. 1 is a front perspective view of a steering wheel showing our new design;

FIG. 2 is a top perspective view thereof; and,

FIG. 3 is a side view thereof the opposite side being a mirror image.

It will be understood that the broken lines presented in the drawings are for illustration only, and do not form a part of the claimed design.
